VALVE FOR ROCK DRILLS

Filed April 9, 1927

FIG.-2.

INVENTOR.
Charles C. Hansen.
BY *Hubert C. Odeon*
HIS ATTORNEY.

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

VALVE FOR ROCK DRILLS

Application filed April 9, 1927. Serial No. 182,322.

This invention relates to rock drills, but more particularly to a distributing valve for a fluid actuated rock drill of the hammer type.

5 The objects of the invention are to obtain a light weight valve capable of effecting a rapid distribution of the pressure fluid to the ends of the cylinder and to insure against trembling of the valve in its extreme positions.

10 Other objects will be in part obvious and in part pointed out hereinafter.

In the drawings illustrating a practical embodiment of the invention.

15 Figure 1 is a longitudinal vertical section of a rock drill showing the valve in one extreme position, and

Figure 2 is a view similar to Figure 1 showing the valve in its other extreme position.

20 Referring to the drawings, the invention is shown embodied in a rock drill comprising a cylinder A having a free exhaust port B. A reciprocatory hammer piston C is disposed in the cylinder A and controls the free exhaust port B. In the present instance a back head D forms a closure for the rearward end of the cylinder and is adapted to overlap the rearward end of a valve chest E. The valve chest E may be formed integrally with the cylinder A as shown and has an annular recess F in which are disposed valve bushings J and K bored to form a valve chamber L for a pressure fluid distributing valve O.

25 In order to centralize the bushings J and K with respect to each other, the bushing J is provided with a short reduced extension P which extends into the rearward end of the bushing K. By so reducing the end of the bushing J a shoulder Q is provided to about the rearward end of the bushing K for holding said bushing K firmly in the forward end of the recess F.

30 The total lengths of the two bushings thus arranged preferably substantially equals the depth of the recess F so that when the back head D is clamped to the cylinder A by the usual side bolts (not shown), the said bushings will be held firmly in operative position by the back head which, in this instance, abuts the rearward end of the bushing J. Prefer-

ably a projection R is formed on the rearward end of the bushing J to extend into an annular recess S in the back head D for preventing leakage of pressure fluid from a passage T in the bushing J and the back head D. The passage T in this instance is in constant communication with the valve chamber L and also with a throttle valve U in the back head, said throttle valve controlling the admission of pressure fluid into the drill.

55 At the juncture of the passage T and the valve chamber L is formed an inlet passage V which leads to the rearward end of the cylinder A. Likewise, an inlet passage W leads from the front end of the valve chamber L to the front end of the cylinder A for conveying pressure fluid thereto to impel the piston C rearwardly.

60 The valve O has a central bore X which conveys pressure fluid through the valve to the front inlet passage W, such pressure fluid in this instance passing from the front end of the valve chamber L into the inlet passage W through ports Y in the end of the bushing K.

65 Intermediate the ends of the valve O is formed an enlarged flange Z having rearward and forward actuating pressure areas b and c respectively. The enlarged flange Z is preferably of slightly greater length than 70 the width of an exhaust port d in the valve chest which it controls.

75 The rearward end e of the valve O is in this instance reduced in diameter to enable said end to extend slidably into a recess g of the bushing J for controlling communication between the passage T and the inlet passage V. The front end f of the valve O is likewise reduced to cooperate slidably with a recess q formed in the front end of the bushing K for controlling communication between the front end of the valve chamber L and the front inlet passage W. By thus reducing the ends of the valve, annular shoulders h are formed on the valve against which 80 pressure fluid may act for holding the valve in its extreme positions.

85 The valve O is actuated by live pressure fluid admitted into the valve chamber L on 90 opposite sides of the flange Z at the most 95 100

suitable period in the cycle of operations of the drill. To that end a kicker port *j* is formed in the valve chest and leads from a point forwardly of the free exhaust port *B* 5 to communicate with the valve chamber *L* rearwardly of the actuating face *b* of the flange *Z*, and a kicker passage *k* leads from the cylinder rearwardly of the exhaust port *B* to the valve chamber *L* forwardly of the 10 actuating pressure area *c* for actuating the valve *O* rearwardly.

In order to prevent centralizing of the valve *O*, said valve is provided with suitable leak ports *o* through which pressure fluid 15 may constantly leak into the valve chamber to act against the actuating pressure areas *b* and *c* to set the valve in operation.

Should the valve *O* assume a neutral position before the drill is set in motion, it 20 will be apparent that the reduced ends of the valve will each be slightly within the recesses *g* and thus prevent pressure fluid from passing over these ends and entering the cylinder to start the piston.

Assuming that the valve is centralized and the flange *Z* thus covering the exhaust port *d*, and if the piston *C* is in the position shown 25 in Figure 1 with the kicker port *k* covered, pressure fluid entering the hollow valve *O* will pass through the leak ports *o* to opposite sides of the flange *Z*. The pressure fluid which enters the lower leak port *o* will pass 30 through the kicker port *j* and exhaust through the free exhaust port *B*.

The pressure fluid which passes through the upper leak port *o* will, however, act upon the pressure area *c* to throw the valve, as the kicker port *k* is covered by the piston and the flange *Z* covers the exhaust port *d*. 35 The tool will thereby be set in motion.

Inasmuch as the kicker ports *j* and *k* are 40 so spaced that they may not be simultaneously covered by the piston *C*, even though the piston *C* overlies the exhaust port *B*, it may happen that the piston will assume a position intermediate these kicker ports without covering either. If the valve then is centralized, it will also be evident that pressure fluid may pass through the leak ports only 45 and enter both ends of the cylinder through the two kicker ports *j* and *k*.

However, due to the difference in area between the front and rear faces of the piston *C*, the pressure fluid entering the rear of the piston through kicker port *j* will build 50 up pressure which will act upon the rear face to overcome the pressure acting upon the front face and thus move the piston until the kicker port *k* is covered thereby. The piston will now be in the position shown in Figure 2 and, as described, the valve will be moved by pressure fluid acting upon the pressure area *c*.

It will be apparent, therefore, that the leak 60 ports *o* will prevent the valve *O* from re-

maining centralized should this condition occur when the tool is to be set in operation. The piston may assume a variety of positions when the valve is centralized but, as will be seen from the instances described, the 70 leak ports will immediately permit pressure fluid to pass and cause the piston to move to a position where one or the other of the kicker ports will be covered whereupon the valve will be moved from its centralized position. 75

As will be observed, the distance which the reduced ends of the valve extend into the recesses *g* is slightly smaller than the travel of the valve required to open communication between the valve chamber and the exhaust port *d*. In this way a supply of pressure fluid will at all times be assured to act against the shoulders *h* for holding the valve in thrown position. 80

The operation of the device is as follows: While the valve *O* is in the position illustrated in Figure 1, pressure fluid flowing through the passage *T* will pass through the inlet passage *V* to the rearward end of the cylinder and actuate the piston forwardly. The pressure fluid thus flowing into the cylinder will act against the rearward shoulder *h* of the valve and hold the valve *O* firmly in its extreme forward position. When the piston *C* uncovers the kicker passage *k*, a portion of pressure fluid will flow into the valve chamber *L* to act against the actuating pressure area *c* for starting the valve rearwardly. After the valve has traveled a slight distance in this direction, the exhaust port *d* will be uncovered by the flange *Z* and the pressure fluid utilized for starting the valve will then be exhausted to the atmosphere. 95

After the valve has been thrown rearwardly, pressure fluid will flow over the front end thereof and, passing through the ports *Y*, front inlet passage *W*, into the front end of the cylinder will impel the piston *C* rearwardly. However, just prior to uncovering of the port *d* the end *f* will have been withdrawn from the recess *g* and pressure fluid then flowing from the front end of the valve will act thereagainst, as well as the front shoulder *h*, to complete the rearward travel of the valve and to hold it in the new position. In this way a comparatively large area of the valve is exposed to pressure fluid for setting it in motion and a considerably smaller area is exposed to fluid for completing the stroke of the valve. The valve is thus exposed to a plurality of impulses for throwing it and inasmuch that the latter of these impulses is a comparatively light force the valve will be prevented from striking heavily against its stop. This is particularly advantageous in valves having a long range of travel. During such admission pressure fluid will then act against the front shoulder 110

h to hold the valve immovable in its rearward position.

Immediately prior to the uncovering of the free exhaust port *B*, the front kicker passage *j* will be uncovered by the piston, and the pressure fluid under full line pressure will then flow through the passage *j* into the valve chamber *L* to act against the actuating pressure area *b* to again start the valve forwardly and after the flange *Z* uncovers the exhaust port *d* the pressure fluid flowing over the rearward end of the valve will act against said end and against the rear shoulder *h* to complete the forward movement of the valve and to hold it in the forward position.

I claim:

1. In a fluid actuated rock drill, the combination of a cylinder and a piston, a valve chest in the cylinder having an exhaust port therein, a hollow distributing valve in the valve chest through which pressure fluid passes, said valve being movable back and forth in the valve chest to admit pressure fluid to one end or the other of the cylinder, a flange on the valve controlling said exhaust port and having relatively large actuating pressure areas upon which pressure fluid from the cylinder may act to move the valve, said movement of the valve serving to partly uncover the exhaust port and permit the exhaust of pressure fluid acting on said actuating pressure areas, reduced ends on the valve adapted to alternately engage the valve chest and prevent the admission of pressure fluid over said ends to the cylinder, and shoulders defined by said reduced ends on the valve, said shoulders and the end surfaces of the valve forming relatively small actuating pressure areas upon which pressure fluid may act and complete the movement of the valve when the exhaust port is uncovered by the flange.

2. In a fluid actuated rock drill, the combination of a cylinder and a piston, a valve chest in the cylinder having an exhaust port therein, a hollow distributing valve in the valve chest through which pressure fluid passes, said valve being movable back and forth in the valve chest to admit pressure fluid to one end or the other of the cylinder, a central flange on the valve controlling said exhaust port and having relatively large actuating pressure areas on each side thereof upon which pressure fluid from the cylinder may act to move the valve, said movement of the valve serving to partly uncover the exhaust port and permit the exhaust of pressure fluid acting on said actuating pressure areas, kicker passages in the cylinder and valve chest for conveying the pressure fluid from the cylinder to said actuating pressure areas, reduced ends on the valve adapted to alternately engage the valve chest and prevent the admission of pressure fluid over said ends to the cylinder, and shoulders defined

by said reduced ends on the valve, said shoulders and the end surfaces of the valve forming relatively small actuating pressure areas upon which pressure fluid may act and complete the movement of the valve when the exhaust port is uncovered by the central flange.

3. In a fluid actuated rock drill, the combination of a cylinder and a piston, a valve chest in the cylinder having an exhaust port therein, a hollow distributing valve in the valve chest through which pressure fluid passes, said valve being movable back and forth in the valve chest to admit pressure fluid to one end or the other of the cylinder, a flange on the valve controlling said exhaust port, reduced ends on the valve adapted to alternately engage the valve chest and prevent the admission of pressure fluid over said ends to the cylinder, and leak ports in the valve through which pressure fluid passes to actuate said valve and start the drill when both ends of the valve are simultaneously engaged by the valve chest.

4. In a fluid actuated rock drill, the combination of a cylinder and a piston, a valve chest in the cylinder having an exhaust port therein, a hollow distributing valve in the valve chest through which pressure fluid passes, said valve being movable back and forth in the valve chest to admit pressure fluid to one end or the other of the cylinder, a flange on the valve controlling said exhaust port and having relatively large actuating pressure areas upon which pressure fluid from the cylinder may act to move the valve, said movement of the valve serving to partly uncover the exhaust port and permit the exhaust of pressure fluid acting on said actuating pressure areas, reduced ends on the valve adapted to alternately engage the valve chest and prevent the admission of pressure fluid over said ends to the cylinder, shoulders defined by said reduced ends on the valve, said shoulders and the end surfaces of the valve forming relatively small actuating pressure areas upon which pressure fluid may act and complete the movement of the valve when the exhaust port is uncovered by the flange, and leak ports in the valve through which pressure fluid passes to actuate said valve and start the drill when both ends of the valve are simultaneously engaged by the valve chest.

In testimony whereof I have signed this specification.

CHARLES C. HANSEN.
